ADJUSTABLE FURNITURE LEG OR SIMILAR ARTICLE

Louis Maslow, Huntsville Road, Dallas, Pa.

Filed Nov. 15, 1961, Ser. No. 67,523

Term of patent 14 years

(Cl. D33—1)

FIGURE 1 is a perspective view of an adjustable furniture leg or similar article showing my new design in exploded form;

I claim:

The ornamental design for an adjustable furniture leg or similar article substantially as shown.
